Thomas M. Dudgeon

UNITED STATES PATENT OFFICE.

THOMAS M. DUDGEON, OF CRAFTON, PENNSYLVANIA, ASSIGNOR TO PITTSBURGH STOVE AND RANGE COMPANY, OF PITTSBURG, PENNSYLVANIA, A CORPORATION OF PENNSYLVANIA.

DESIGN FOR A FIREPLACE-FRONT.

SPECIFICATION forming part of Design No. 36,069, dated September 9, 1902.

Application filed July 29, 1902. Serial No. 117,588. Term of patent 7 years.

To all whom it may concern:

Be it known that I, THOMAS M. DUDGEON, a citizen of the United States, residing at Crafton, in the county of Allegheny and State of Pennsylvania, have invented a new, original, and ornamental Design for Fireplace-Fronts, of which the following is a full, clear, and exact description, reference being had to the accompanying drawing, forming part hereof, in which the invention is shown in front elevation.

The leading features of my design consist in a frame the sides of which have scrolled inner and outer edges. The cross-piece, which is in the form of a hood, has scrollwork at the corners and a scrolled upper edge. The hooded portion proper has a wavy or undulating lower edge, and its upper surface is separated into variously-shaped portions by diversely-extending scrolls and meeting lines. The cen-

ter or summer front shows in the background a lake and mountain scene. In the foreground the figures of three boys are seen, one standing on an ornamental walled platform and playing on a violin and the others sitting on the edge of the platform and playing the one on a mandolin and the other on a harp. Surmounting the column at one corner of the platform is a flower-urn with a palm-plant contained therein. At the other side of the platform a palm-tree is seen.

I claim—

The ornamental design for a fireplace-front as described and shown.

In witness whereof I have hereunto set my hand.

THOMAS M. DUDGEON.
